C. E. GODLEY.

LAMP.

APPLICATION FILED NOV. 28, 1913.

1,097,621.

Patented May 26, 1914.

UNITED STATES PATENT OFFICE.

CHARLES E. GODLEY, OF DETROIT, MICHIGAN, ASSIGNOR TO EDMUNDS AND JONES MANUFACTURING COMPANY, OF DETROIT, MICHIGAN, A CORPORATION OF MICHIGAN.

LAMP.

1,097,621.

Specification of Letters Patent.

Patented May 26, 1914.

Application filed November 28, 1913. Serial No. 803,390.

To all whom it may concern:

Be it known that I, CHARLES E. GODLEY, a citizen of the United States, and a resident of Detroit, in the county of Wayne and State of Michigan, have invented a new and Improved Lamp, of which the following is a specification.

This invention relates to lamps, especially to those adapted for vehicles, and its objects are, first:—to provide means whereby the font and burner may be readily attached to and disconnected from the body; second:—to provide means whereby rattling is effectually prevented; third:—to provide means whereby a seal is automatically effected between the burner and the font whenever they are inserted within the body; and fourth:—to provide an automatic seal between the body and the font whenever the font is inserted into the body.

To accomplish the first and second objects mentioned, this invention consists in a series of faces on one of the members, said faces comprising inclined portions, a series of projections on another member, and a spring upon the body to prevent disengagement of the projections from the faces.

To accomplish the third object mentioned, this invention comprises a slip-joint between the burner section and the font and a washer that seals the joint when the font and burner are inserted into the body portion against the tension of the spring therein.

To accomplish the fourth object mentioned, this invention comprises an upstanding neck on the font, and a spring plate mounted in the body with which the neck closely engages when the parts are assembled.

This invention also comprises the various details of construction shown and described, and more particularly pointed out in the claims.

In the drawings, Figure 1 is a front elevation of the lamp. Fig. 2 is a central vertical section, the upper portion of the lamp being omitted. Fig. 3 is a vertical section of the member that connects the lamp body to the font. Fig. 4 is a section on the line 4—4 of Fig. 3. Fig. 5 is a vertical section of the font.

Similar reference characters indicate like parts throughout the several views.

The lamp comprises a top 1, a body 2 hav-

ing a bottom or connecting piece 3, a burner 4, and a font 5.

The font consists of a globular bowl 10, preferably formed from a single piece of metal, and a cylindrical neck 11 projecting upwardly therefrom, the part 10 merging 60 into the neck in a reentrant bead 12, whose inner upper surface constitutes an annular shoulder 13. Seated within the neck and resting upon the shoulder is a cover plate 15, preferably having an upstanding cylindrical 65 edge 16 that may be soldered or otherwise secured to the neck, and a central annular depression 17, the inner edge of which terminates in a downwardly depending cylinder 18. The neck 11 has a slot 20 formed 70 therein parallel to the axis of the font, and has projecting from its outer surface a series of pins 21, preferably three, one of which is shown in elevation in Fig. 2.

Seated upon the font is a burner 4 comprising an annular outwardly extending portion 25 and a downwardly depending skirt 26, that incloses the perforated draft plate 27 having a cylindrical extension 28 at its lower end. The lower end of the cylindrical extension 28 may have formed integrally therewith an inturned annulus 29, the inner edge of which is curved downwardly and outwardly to form a bead 30, below which a cylinder 31 extends, and may 85 have an inturned annular edge 32. The wick tube 33, having the skirt 34 thereon, is mounted in the burner section in the usual manner, and a wick shaft 35 passes through and is seated in the walls of the 90 cylindrical extension 28. A thumb-piece 36 may be secured upon its outer end.

A washer 37, that may be of leather or any other desired material, is seated in the bead 30 and rests within the annular depression 17 in the font to constitute a seal between the annulus 29 of the burner section and the font.

The connecting piece 3 of the body comprises an upper member having an upstanding edge 41 that may be soldered to the body 2, an annular portion 42, and a downwardly depending circular edge 43, that is received within a circular bead 44 formed upon the upper edge of a lower member 45. This 105 lower member is also provided, near its upper edge, with an inwardly opening bead 46, that forms a seat for an annular spring

plate 47 having an upturned inner edge 48 terminating in a series of upwardly and inwardly projecting springs 49. The lower edge of the member 45 is reversely bent to form an inner wall 55 whose internal diameter is substantially equal to the external diameter of the cylindrical neck 11 on the font 5. The internal wall is cut away at a series of points, corresponding in number and angular location to the pins 21, to form openings through which the said pins may be inserted. The wall 55 at one side of each of the openings is preferably vertical, while the portion 57 at the other side is inclined and terminates in a ledge 58 having a rear edge 59.

The outer wall of the lower member 45 is cut away to form a slot 60 that has an inclined upper end 61, and the inner wall 55 is correspondingly cut away to form an inclined face 62, the slot 60 being adapted to receive therein the wick shaft 35.

A reflector 65 may be supported in the body if desired, as indicated in Fig. 2.

25 Operation: The washer 37 should be placed in position within the bead 30, after which the burner may be inserted into the opening in the font. The cylindrical neck 11 of the font is then arranged in alinement with the inner face of the cylindrical wall 55 of the connecting piece 3, and the font and burner are turned angularly until the pins 21 and the wick shaft 35 register with the openings in the inner wall 55 and the slot 60, respectively. The font and burner may then be thrust longitudinally in respect to the connecting piece 3 against the action of the springs 49, a movement that carries the pins 21 and the shaft 35 into the respective openings in the member 3, after which the body and font may be turned angularly in respect to each other in the proper direction to carry the pins up the inclined faces 57 and beyond the ledges 58. Upon the longitudinal pressure being reduced, the springs 49 force the font outwardly in respect to the lamp body, which causes the pins to seat themselves behind the ledges 58, thus effectually preventing accidental disengagement of the parts. The springs 49 at the same time exert a pressure upon the annular portion 25 of the burner, and, through it, upon the washer 37, thereby sealing the joint between the font and the burner. At the same time, the neck 11 engages snugly within the upstanding inner edge 48 of the spring plate 47 to form a seal between the body and the font.

It is obvious that many changes may be made in the details of construction without departing from the spirit of my invention.

Having now described my construction, what I regard as my invention and desire to secure by Letters Patent is:—

65 1. In a lamp, the combination of a body, a

font telescopically connected to the body, a burner having a plain socket engagement with the font, a spring seated in the body and engaging the burner and tending to force the burner against the font, and means 70 for connecting the font and body and tensioning the spring.

2. In a lamp, a body, a burner therein, a spring seated in the body and engaging the burner, a font upon which the burner is 75 mounted, said spring tending to force the burner against the font, and means for retaining the font and burner in position with respect to the body and tensioning the spring.

3. In a lamp, the combination of two members and a burner, a spring seated in one of the members and engaging the burner, said spring tending to force the burner against the other member, and means on 85 one of the members co-acting with means on the other member to retain the burner in position and tension the spring.

4. In a lamp, the combination of two members and a burner, a spring seated in 90 one of the members and engaging the burner, said spring tending to force the burner against the other member, pins on one of the members co-acting with inclined faces on the other member to retain the burner in 95 position and tension the spring.

5. In a lamp, the combination of a font, a lamp body, a burner therein, a circumferential spring seated in the body having inwardly extending arms engaging the burner, 100 said spring tending to force the burner against the font, pins projecting laterally from the font, and locking means on the lamp body adapted to engage with the pins to hold the font and burner in position on 105 the body and tensioning the spring, said locking means comprising inclined faces terminating in ledges and a depression beyond each ledge.

6. In a lamp, the combination of two 110 members and a burner, resilient means seated in one of the members and engaging the burner, said resilient means tending to force the burner against the other member, pins on one of the members co-acting with inclined faces on the other member to cause the two members to approach each other and tension the resilient means when they are turned angularly in respect to each other, 115 said inclined faces terminating in ledges and depressions beyond the ledges wherein the pins may seat themselves at the end of the angular turning movement, said pins being held in said depressions by the force of the resilient means.

7. In a lamp, the combination of a body, a burner therein, a spring seated in the body and engaging the burner, a font, a slip joint between the burner and font, means for sealing said joint, said spring tending to 130

force the burner and the font away from the body, and means on the font co-acting with means on the body to retain the font and burner in position on the body and tension 5 the spring.

8. In a lamp, the combination of a body, a burner therein, a spring seated in the body and engaging the burner, a font, a slip joint between the burner and font, a washer for 10 sealing said joint, said spring tending to force the burner and the font away from the body, pins projecting laterally from the font, and inclined faces on the body whereby the font and the burner are held in position on the body and the spring is tensioned 15 and the sealing washer is held in position to seal the joint between the font and the burner.

9. In a lamp, the combination of a body, 20 a burner therein, a wick shaft for the burner, a spring mounted in the body and engaging the burner, a font to which the burner is secured, the spring tending to force the burner against the font, said font being provided with outwardly projecting pins, a 25 connecting piece on the body and comprising an outer wall and a reversely bent inner

wall having openings and inclined faces to receive the pins on the font, said outer wall having a slot including an inclined portion, 30 and the inner wall being cut away to register with the slot, said slot and cut away portion forming an opening for the passage of the wick shaft.

10. In a lamp, the combination of a body, 35 a burner therein, a spring seated in the body and engaging the burner, said spring comprising an upstanding circular inner edge, a font to which the burner is connected, said font having a cylindrical neck of such diameter that it fits snugly within the upstanding inner edge of the spring to constitute a seal between the font and the body, the spring tending to force the burner against the font, and means to secure the 40 font and burner in the body and tension the spring.

In testimony whereof I have signed this specification in the presence of two subscribing witnesses.

CHARLES E. GODLEY.
